SWAGING MACHINE

Julius B. Tiedemann, Milwaukee, Wis., assignor
to A. O. Smith Corporation, Milwaukee, Wis., a
corporation of New York

Application August 8, 1940, Serial No. 351,881

7 Claims. (Cl. 80—14)

This invention relates to swaging machines and constitutes an improvement on the machine illustrated in my co-pending application, Serial No. 276,046, filed May 27, 1939, for Pipe swaging machine. This application is a continuation in part of said former application.

One of the objects of the invention is to provide shorter and more sturdy bearings for the crank shafts which drive the swaging dies.

Another object is to locate the cranks and links in a housing away from oil and dirt and spray which may be thrown from the dies in operation.

Another object is to provide a balancing of the load on the crank shaft to prevent undue stress of the same.

Another object is to provide a machine having greater access to the dies for changing dies and repair purpose.

Other objects will be set forth hereinafter in connection with the description of one embodiment of the invention illustrated in the accompanying drawing.

In the drawing:

Figure 1 is a side elevation of the machine with parts broken away and in section and with parts shown dotted; and

Fig. 2 is an end elevation of the machine with parts broken away and in section.

The base 1 of the machine is suitably secured to a foundation 2 and has a pair of side housings 3 extending upwardly for the full height of the machine. Each of the side housings comprises two relatively thick plates 4 and 5 disposed vertically in parallel spaced relation, and removable closure plates 6 joining the corresponding vertical edges of plates 4 and 5 to complete the closure. Top and bottom plates 7 are welded or otherwise secured to the vertical plates to hold the same in fixed position.

The vertical plates 4 and 5 of the two housings have lower aligned bearings 8 for receiving the lower crank shaft 9 and upper aligned bearings 10 for receiving the upper crank shaft 11 located vertically above the shaft 9 and parallel thereto. Gears 12 keyed to the ends of the shafts 9 and 11 provide a synchronous drive therefore from a suitable power source, not shown.

Flanged sleeves 13 enclose the central portions of shafts 9 and 11 and are bolted to the inner flanges of bearings 8 and 10 to protect the bearings from grit and to retain the lubricating oil.

The swaging dies 14 and 15 are located in the center of the machine one above the other, between the inner housing plates 4, and have suit-

able curved recessed faces for receiving a pipe 16 fed horizontally to the machine between strokes of the dies. Each die has a trunnion 17 extending laterally from the sides near each end and through a slot 18 in the respective plate 5. There are four lateral trunnions for each die.

The upper shaft 11 has two pairs of eccentric cranks 19 located in the housings, the cranks of each pair extending in substantially opposite directions from the center of the shaft, and one of the cranks of each pair is connected to the respective rear trunnion 17 of the upper die 14 by means of a link 20 while the other crank of each pair is connected to the respective forward trunnion 17 of the upper die 14 by means of a link 21, so that the die 14 is suspended from the upper shaft 11 and its movement is prescribed by the cranks 19 on that shaft.

Likewise, the lower shaft 9 has two eccentric cranks 22 located in each housing and connected respectively to the rear and the forward trunnions 17 of the lower die 15 by links 23 and 24, so that the die 15 is supported by the lower shaft 9 and its movement is prescribed by the cranks 22 on that shaft.

The general movement and operation of the dies 14 and 15 is similar to that set forth in the co-pending application above referred to. In order to more effectively control and synchronize the movement of the dies, the respective rear trunnions 17 of the two dies are connected together and to the housings by links 25 which pivot on cross pins 26 extending between plates 4 and 5 of each housing in approximately the horizontal plane of the axis of the pipe 16.

Wear plates 27 are secured to the inner surface of each housing plate 5 between it and the ends of trunnions 17 and serve to keep the dies in vertical alignment. Plates 28 are secured on the sides of each die and serve to cover the various openings in the plates to prevent dirt from getting into the links and bearings in the housings.

By locating the cranks and links in side housings the bearings for the shafts are disposed closer together and to the cranks so that there is less tendency for the shafts to bend and produce inaccuracies in die movement, the cranks and links have their bearing surfaces protected from dirt and disposed for easy oiling, the oil for the moving drive parts is kept clean, the dies are left relatively open for ready repair and replacements of die segments, and the machine is more efficient in its application of power and can be of lighter weight construction. Other ad-

vantages lie in the cheaper and simpler construction and assembly.

The cranks 19 are in pairs in each housing, and likewise cranks 22 are in pairs. The cranks of any one pair extend in opposite directions from the center of the shaft. Link 20 joins one crank 19 to the rear trunnion while link 21 of substantially the same length as link 20 joins the other crank 19 to the forward trunnion. The connections to the respective cranks are made to provide that during the working stroke the cranks are disposed on the same side of the shaft as the respective trunnion linked thereto. This provides for a transfer of stress as nearly vertical to the dies as possible and as the stroke progresses the static stress on the shaft at any given time is as nearly balanced as possible. During the period of the working stroke when one link is stressed more than the other the more heavily stressed link is disposed more nearly in the direction of a line between the center of the shaft and the center of the trunnion to which the link is pivoted.

Various embodiments of the invention may be employed within the scope and intent of the invention as expressed in the accompanying claims.

The invention is claimed as follows:

1. A swaging machine comprising a pair of reciprocating swaging dies, a housing disposed on each side of the dies and containing mechanism for operating the dies, means extending through slots in the housings for connecting said mechanism with the dies to drive the latter, and means moving with said last named means for closing said slots to prevent access of dirt and scale from the swaging operations to the mechanism in the housing.

2. A swaging machine comprising a pair of reciprocating swaging dies, a housing disposed on opposite sides of the dies, trunnions on the sides of the dies and extending into the housings through slots in the walls of the housing, a pair of crank shafts extending through each housing and having bearings in the walls of the housing and cranks disposed within the housing, 45 links joining said cranks to the respective die trunnions in the housing for operating the dies from the crank shafts, and means for driving said crank shafts in synchronism.

3. A swaging machine comprising a reciprocating rocking swaging die, a shaft having end bearings and disposed transversely of the die, and a pair of links disposed in a housing on each side of the die and connecting the opposite ends of the die to cranks on said shaft, the pairs of links being separated by said die to locate the cranks adjacent the end bearings for said shaft.

4. A swaging machine comprising a reciprocating rocking swaging die, a shaft disposed transversely of the die, a pair of links on each side of the die connecting the opposite ends thereof to cranks on said shaft, a housing on each side of said dies for enclosing said links and cranks, and bearings for said shaft disposed closely adjacent and on opposite sides of each pair of cranks.

5. A swaging machine comprising a base having two spaced upstanding housings between which the swaging dies are disposed one above the other, an upper crank shaft extending through said housings above the dies and a lower crank shaft extending through said housings below the dies, bearings for said shafts in the opposite walls of each housing, side trunnions on said dies at each end extending through slots into said housings, a pair of cranks on each shaft in each housing, links joining the cranks on the upper shaft to respective die trunnions of the upper die, and links joining the cranks on the lower shaft to respective die trunnions of the lower die.

6. A swaging machine comprising a base having two spaced upstanding housings between which the swaging dies are disposed one above the other, an upper crank shaft extending through said housings above the dies and a lower crank shaft extending through said housings below the dies, bearings for said shafts in the opposite walls of each housing, side trunnions on said dies at each end extending through slots into said housings, a pair of cranks on each shaft in each housing, links joining the cranks on the upper shaft to respective die trunnions of the upper die, links joining the cranks on the lower shaft to respective die trunnions of the lower die, and means for closing said slots against access of dirt from the swaging operations to the mechanism in the housings.

7. In a swaging machine, a swaging die disposed for reciprocatory rocking and orbit movement, a rotary crank shaft disposed transversely of the die for operating the same and having a pair of cranks thereon extending in substantially opposite directions from the center of the crank shaft, means connecting said cranks to opposite ends of the die and of substantially equal length to provide a working stroke for the die in which the cranks are on the same side of the shaft as the respective ends of the die to which they are linked, and in which each link extends in substantially the plane of the shaft and of the connection to the die during the period of maximum load thereon.

JULIUS B. TIEDEMANN.
